RAZOR

James E. Connolly, Baltimore, Md.

Application May 14, 1945, Serial No. 593,552

17 Claims.

(Cl. 30—65)

1

This invention relates to safety razors and more particularly to safety razors of the type including a guard, a head, and means for drawing or holding the guard and head together to clamp between them a wafer type flexible blade.

In many razors of this kind the head is provided with a threaded stem adapted to extend through apertures in the blade and the guard and to receive the interiorly threaded end of a shank or handle which when screwed up tightly on the stem, draws the guard and head together so as to clamp the blade in operative position. The guard is equipped with locating means such as a rib or set of lugs for aligning the blade.

Most blades now used with razors of this class are formed with a central aperture or slot which has to be slipped over the head's threaded stem before the guard is applied. Frequently the walls of the blade aperture or slot catch on the threads of the stem making it necessary to jiggle the blade a little to dislodge it from the threads. Thus considerable care is required to position the blade on the head. Often, when the thin, delicate blade is handled carelessly by a heavy-handed person it catches on the threads, is forced and broken.

In accordance with the present invention these difficulties are eliminated by providing a construction in which the blade is formed with a slot adapted to receive a guiding part on the head, such as a rib or lug, the blade then being moved endwise into cooperative position with respect to the head. It heretofore has been proposed to provide a wafer blade with an open ended slot adapted to receive a guide rib on a safety razor head so that the blade may be slid endwise into operative position. In such prior constructions the blade fits loosely or freely on the head and is easily displaceable from the head by even a slight jarring or tipping. It is necessary for the user to hold the blade on the head carefully until after the guard has been applied.

An object of the present invention is to provide a head and blade for a razor of the class referred to in which the blade can be positioned on the head by endwise movement and guided to operative position by a rib, lug, or the like on the head extending into a slot in the blade, there being means on the head for holding the blade bowed transversely, whereby accidental displacement of the blade from the head is resisted. The blade is thus yieldingly or resiliently connected to the head and will hold its position on the head while the guard is being applied.

Another object of the invention is to provide a

2

construction in which the blade slot is open at one end and extends substantially throughout the length of the blade, the open end of the slot being adapted to be passed over a guiding part on the head, and the blade being engaged with a shoulder or other surface on the head for bowing the blade transversely.

Another object is to provide a head and blade assembly in which the blade is held bowed by the head itself, the blade having a slot extending from one end only partially to the other end and terminating in a blade inner bridge piece beyond which the blade is formed with an opening for receiving a projection on the head.

Another object is to provide a blade and head construction of the kind in which the blade has an open ended slot adapted to receive a guide part on the head so that the blade may be moved endwise into position, the end of the blade opposite the open end of the slot being formed with a tab or the like which can be grasped easily for removing the blade from the head.

Another object of the invention is to provide a complete razor assembly including a head, blade, and guard, the head and blade being so constructed that the blade is resiliently held in position on the head before the guard is placed in blade clamping position.

A further object is to provide an improved razor head and blade assembly in which the blade has a long open ended slot and the head has means for engaging the corners of the blades adjacent the slot open end for preventing the blade from spreading.

Other objects will become apparent from a reading of the following detailed description, the appended claims, and the accompanying drawings in which:

Figure 1 is a perspective view of a razor blade and head embodying the invention in one form, the blade being shown as being only partially applied to the head and the longitudinal flexing of the blade being exaggerated for clearness of illustration.

Figure 2 is a transverse section of the blade and head shown in Figure 1 but with the blade shown in its cooperative or assembled position with respect to the head.

Figure 3 is a side view showing the head in longitudinal section and the blade in elevation, the blade being shown in an intermediate position occupied during its endwise movement into cooperative position with respect to the head.

Figure 4 is a transverse sectional view of the assembled head and blade shown in Figures 1, 2

and 3 in connection also with a guard and handle, all of the parts being shown in completely assembled position ready for use.

Figure 5 is a longitudinal sectional view of the assembly shown in Figure 4.

Figure 6 is a plan view of a razor guard looking at the face thereof which is adapted to be positioned next to the razor blade.

Figure 7 is a fragmentary assembly plan view showing one end of the head and the adjacent end of the blade of the construction shown in Figures 1 to 6, inclusive.

Figure 8 is a view similar to Figure 1 but showing a modified construction.

Figure 9 is a transverse sectional view of the blade and head shown in Figure 8, the blade being shown in its cooperative position with respect to the head.

Figure 10 is a view showing the blade and head illustrated in Figures 8 and 9, the head being shown in longitudinal section and the blade in side elevation in an intermediate position occupied during its endwise movement on the head.

Figure 11 is a plan view of a guard adapted to be assembled in connection with the head and blade shown in Figures 8 to 10, inclusive.

Figure 12 is a view similar to Figure 1 but showing a further modified construction.

Figure 13 is a transverse sectional view of the blade and head shown in Figure 12, the blade being shown in its cooperative position with respect to the head.

Figure 14 is a view showing the blade and head illustrated in Figures 12 and 13, the head being shown in longitudinal section and the blade in side elevation in an intermediate position occupied during its endwise movement on the head; and

Figure 15 is a plan view of a guard adapted to be assembled in connection with the head and blade shown in Figures 12 to 14, inclusive.

The embodiment of the invention shown in Figures 1 to 7, inclusive, includes a head member A, a flexible wafer type blade B, a guard member C, and a shank or handle D. The blade is adapted to be positioned between the head A and guard B which may be drawn or held together by cooperation of a threaded stud 1 on the head A and an internally threaded bore 2 in the end of the handle D.

The blade B is formed with an open ended slot 3 which extends from the left hand end of the blade, as viewed in Figures 1, 3 and 5, toward the right, terminating in a single bridge piece 4 which joins the portions of the blade on opposite sides of the slot 3. The blade may be formed along both sides of the slot 3 with stress relief openings or transverse grooves of any suitable size and configuration. The two opposed cutting edges of the blade are indicated at 5.

The head A is curved or bowed transversely, and is formed on its concave face with a longitudinally extending rib part 6 which is adapted to be received by the blade slot 3 for guiding the blade B when it is moved endwise into cooperative position with respect to the head A. In order that the blade B may be held releasably and yieldingly in its cooperative position the head is formed with a collar 7 surrounding the stud 1 adjacent its junction with the rib 6, the collar 7 providing a shoulder 8 under which the blade passes when being moved endwise into position on the head.

In accordance with the invention, the shoulder 8 is so positioned with respect to the longitudinal

edges of the head A as to cause the blade B, when cooperatively positioned on the head, to be bowed transversely. To this end the shoulder 8 preferably is located between the longitudinal central portion of the head's concave face and a plane containing the head's longitudinal side edges. It will be seen, particularly from a consideration of Figure 2, that this positioning of the shoulder 8 with respect to other parts of the head A causes the blade B to be held in the desired transversely bowed state. Consequently, the blade will not become detached from the head accidentally before the guard C is put into place as shown in Figures 4 and 5. When the guard C is put in place and screwed down tight by the handle D the blade will be clamped in the position shown in Figure 4 which corresponds to the positioning of blades in conventional razors of this type.

In accordance with a further feature of the invention the razor head and the end of the blade adjacent the open end of the slot are cooperatively formed or related to resist spreading of the blade when it is clamped between the head A and guard C. In the form shown, the blade B is formed with centering faces 9 which are disposed inwardly from the cutting edges 5 and between the cutting edges and the slot 3. The blade also is formed with transversely extending locating faces 10. When the blade is moved endwise into position on the head the surfaces 10 will engage blade centering lugs 11 on the head so as to limit the blade's endwise movement. The lugs 11 are tapered from their outer edges downwardly and inwardly toward the center of the head A so that if the blade has any tendency to spread adjacent the open end of the slot, downward pressure exerted on the blade by the head C will force the centering faces 9 against the inclined surfaces of the lugs 11 which will cause the faces 9 and the associated blade portions to be cammed or squeezed inwardly toward the blade's longitudinal axis.

The lugs 11 are provided at each of the corners of the head A so that when the blade is moved endwise into position on the head the blade must pass over the lugs 11 at the end of the head from which the blade is being introduced. The lugs 11 extend upwardly above the shoulder 8 so that the blade B must be bowed longitudinally as well as transversely while it is passing over the lugs 11 as shown in Figures 1 and 3. After the blade has been moved to the left as viewed in Figures 1 and 3 far enough for the blade faces 10 at the left of the blade to engage the head lugs 11 the blade faces 10 at the right of the blade will pass beyond the adjacent head lugs 11 whereupon the blade will move down into the position shown in Figure 2 in which the blade is bowed transversely but not longitudinally.

As shown in Figure 6, the guard C is formed with the usual longitudinal recess 12 adapted to receive the head rib 6 and is further provided with a counterbore or circular recess 13 adapted to receive the head collar 7 so as to enable the guard to be brought up close to the blade and head as shown in Figures 4 and 5.

In order to facilitate removal of the blade endwise from the head, the blade may be provided with a lug or tab 14 projecting out of the plane of the blade from the bridge piece 4. Grasping of the tab 14 is facilitated by providing the head 75 A with end cut-outs or recesses 15 adapted to

accommodate the tab 14 and render it easily accessible.

The modified construction shown in Figures 8 to 11 is similar to that described with reference to Figures 1 to 7 in that the blade is bowed both transversely and longitudinally while being applied endwise to the head but differs from the previously described form in that the blade embodied in the modified form has a central slot extending only partially throughout its length and the head is modified in order to cooperate with the shorter blade slot. The head A', shown in Figures 8 to 11, inclusive, is similar to the head A shown in Figures 1 to 7, inclusive, with the exception that its longitudinal rib 16 extends from the left hand end of the head only to the threaded stem 1', a separate projection or short rib 17 being provided at the right hand end of the head in longitudinally spaced relation to the rib 16. The projection 17 is at least as high as the distance between the shoulder 8' and the longitudinal center of the head concave face. The other parts of the head A' are similar to corresponding parts in the previously described form and are designated by corresponding reference characters which, however, are primed. For example, the head A' shown in Figures 8 to 11, inclusive, has a collar 1' and a shoulder 8' which correspond to the collar 7 and shoulder 8 embodied in the head A shown in Figures 1 to 7, inclusive.

The blade B' embodied in the form shown in Figures 8 to 11, inclusive, has a short slot 18 extending from the left hand end of the blade slightly beyond the center of the blade so as to terminate at an inner bridge piece 19 beyond which is a blade opening 20 adapted to accommodate the head projection 17. Otherwise the parts of the blade B' are similar to corresponding parts of the blade B and are designated by corresponding reference numerals which, however, are primed. Thus, the blade B' has a right hand bridge piece 4' and cutting edges 5' corresponding, respectively, to the bridge piece 4 and cutting edges 5 of the blade B.

In order to position the blade B' on the head A' the open end of the slot 18 is passed from right to left over the head rib 16 and under the shoulder 8'. During its movement to the left the blade B' will be bowed transversely and longitudinally, as previously explained, and when the left hand blade faces 10' engage the left hand head lugs 11' the blade opening 20 will register with the head projection 17 and the right hand end of the blade may be moved down into final position on the head with the blade bowed only transversely, as shown in Figure 9.

The guard C', shown in Figure 11, has a longitudinal recess 21 adapted to receive the head rib 16, a circular recess 13' adapted to receive the collar 1', and a short longitudinal recess 22 adapted to receive the head projection 17. No handle is shown in connection with the parts illustrated in Figures 8 to 11, inclusive, but it will be apparent that a handle the same as the handle D previously referred to may be used.

The further modification shown in Figures 12 to 15, inclusive, also is generally similar to the form illustrated in Figures 1 to 7, inclusive, in that the blade is bowed both transversely and longitudinally while being moved into position on the head and is bowed only transversely when in its final cooperative position. The head A' shown in Figures 12 to 14 is formed with a longitudinally extending rib 23 and a flange 24 at the

5 top of that portion of the rib 23 extending from the left hand end of the head to a point just beyond the threaded stem 1''. The bottom overhanging faces of the flange 24 provide shoulders under which the blade B is moved endwise. Thus, the flange 24 with its shoulders 25 performs in a broad sense the same function as the round collar 7 and shoulder 8 in the embodiment shown in Figures 1 to 7, inclusive. The other parts of the head A'' are similar to corresponding parts of the head A and are designated by corresponding but double primed reference numerals.

10 The blade B, shown in Figures 12 to 15, inclusive, may be and is shown as being precisely the same as the blade B illustrated in Figures 1 to 7, inclusive. However, the guard C'' differs in that it is formed with a longitudinally extending narrow recess 21 adapted to receive the head rib 23 and with a longitudinally extending relatively 15 wide recess 26 adapted to accommodate the flange 24.

15 The blade B, shown in Figures 12 to 15, inclusive, may be and is shown as being precisely the same as the blade B illustrated in Figures 1 to 7, inclusive. However, the guard C'' differs in that it is formed with a longitudinally extending narrow recess 21 adapted to receive the head rib 23 and with a longitudinally extending relatively 20 wide recess 26 adapted to accommodate the flange 24.

25 It will be apparent that in each of the embodiments shown for the purposes of illustrating the broad principles of the invention the head and blade are so cooperatively constructed and arranged that, prior to the application of the guard, the blade will be held yieldingly in a transversely bowed condition on the head. The resiliency of the blade resists accidental displacement of the blade from the head so that while the guard is being applied to the assembled blade and head there is no likelihood that the blade will jiggle off. This eliminates a difficulty that heretofore has caused considerable annoyance and breakage and dulling of many razor blades.

30 35 The constructions disclosed for the purpose of illustration embody the invention in the forms now preferred but it will be apparent that the invention may be embodied in other forms without departing from the invention as defined in the claims.

I claim:

1. A clamping head for a safety razor of the type including a guard; a head; and means for holding said head and guard together to clamp therebetween a wafer type blade having a longitudinal slot, said head having a part adapted to be received in the blade slot for guiding the blade endwise into cooperative position with respect to 40 said head, and shoulder means under which the so positioned blade lies, said shoulder means being disposed below a plane containing the longitudinal edges of said head whereby said shoulder means and said longitudinal edges will hold 45 said head, and shoulder means under which the so positioned blade lies, said shoulder means being disposed below a plane containing the longitudinal edges of said head whereby said shoulder means and said longitudinal edges will hold 50 said head, and shoulder means under which the so positioned blade lies, said shoulder means being disposed below a plane containing the longitudinal edges of said head whereby said shoulder means and said longitudinal edges will hold 55 the blade bowed longitudinally to resist accidental displacement of the blade from the head.

2. A clamping head for a safety razor of the type including a guard; a head; and means for holding said head and guard together to clamp 60 therebetween a wafer type blade having a longitudinal slot, said head being curved transversely and having a part on its concave face adapted to be received in the blade slot for guiding the blade endwise into cooperative position with respect to 65 said head, and shoulder means under which the so positioned blade lies, said shoulder means being disposed between a plane containing the head's longitudinal edges and the longitudinal center of the head's concave face whereby 70 said shoulder means and said longitudinal edges will hold the blade bowed transversely to resist accidental displacement of the blade from the head.

3. A clamping head for a safety razor of the type including a guard; a head; and means for

holding said head and guard together to clamp therebetween a wafer type blade having a longitudinal slot, said head being curved transversely and having blade centering lugs at its corners on its concave face, a part adapted to be received in the blade slot for guiding the blade endwise into cooperative position with respect to said head, and shoulder means under which the blade moves endwise into said position, said shoulder means being disposed between the longitudinal center of the head's concave face and a plane containing the head's longitudinal edges whereby the blade will have to be bowed both transversely and longitudinally when being moved endwise into position and the shoulder means and head longitudinal edges will hold the positioned blade bowed transversely to yieldingly resist accidental displacement of the blade from the head.

4. A clamping head for a safety razor of the type including a guard; a head; and means for holding said head and guard together to clamp therebetween a wafer type blade having a longitudinal slot, said head being curved transversely and having a longitudinally extending rib on its concave face adapted to be received in the blade slot for guiding the blade endwise into cooperative position with respect to said head, and a collar on said rib providing a shoulder spaced from and facing said head and being adapted to overlie a blade cooperatively positioned on said head, said shoulder means being disposed between the longitudinal center of the head's concave face and a plane containing the head's longitudinal edges, whereby a cooperatively positioned blade will be held bowed transversely and displacement of the blade from the head will be yieldingly resisted.

5. A clamping head for a safety razor of the type including a guard; a head; and means for holding said head and guard together to clamp therebetween a wafer type blade having a longitudinal slot extending from one end of the blade only part way to the other end thereof and terminating at an inner bridge piece beyond which there is an opening in the blade and, beyond said opening, an outer bridge piece, said head being curved transversely and having a rib on its concave face extending longitudinally from one end of the head and terminating adjacent the head center and being adapted to be received in the blade slot for guiding the blade endwise into cooperative position with respect to the head, a projection on the head's concave face spaced longitudinally from said rib and being adapted to be received by said blade opening, and shoulder means under which a cooperatively positioned blade lies, said shoulder means being disposed between the longitudinal center of the head's concave face and a plane containing the head's longitudinal edges whereby a cooperatively positioned blade will be held bowed transversely and displacement of the blade from the head will be yieldingly resisted.

6. A clamping head for a safety razor of the type including a guard; a head; and means for holding said head and guard together to clamp therebetween a wafer type blade having a longitudinal slot extending from one end of the blade only part way to the other end thereof and terminating at an inner bridge piece beyond which there is an opening in the blade and, beyond said opening, an outer bridge piece, said head being curved transversely and having a rib on its concave face extending longitudinally from one end of the head and terminating adjacent the head

center and being adapted to be received in the blade slot for guiding the blade endwise into cooperative position with respect to the head, a projection on the head's concave face spaced longitudinally from said rib and being adapted to be received by said blade opening, and shoulder means under which a cooperatively positioned blade lies, said projection being at least as high as the distance between said shoulder means and said head's concave face whereby when the blade is being moved endwise into said cooperative position the blade must be bowed longitudinally to enable said inner bridge piece to pass over said projection so that the projection may then enter said blade opening for maintaining the blade against accidental displacement from said head.

7. A clamping head for a safety razor of the type including a guard; a head; and means for holding said head and guard together to clamp therebetween a wafer type blade having a longitudinal slot extending from one end of the blade only part way to the other end thereof and terminating at an inner bridge piece beyond which there is an opening in the blade and, beyond said opening, an outer bridge piece, said head being curved transversely and having a rib on its concave face extending longitudinally from one end of the head and terminating adjacent the head center and being adapted to be received in the blade slot for guiding the blade endwise into cooperative position with respect to the head, a projection on the head concave face spaced longitudinally from said rib and being adapted to be received by said blade opening, and shoulder means under which a cooperatively positioned blade lies, said projection being at least as high as the distance between said shoulder means and said head's concave face whereby when the blade is being moved endwise into said cooperative position the blade must be bowed longitudinally to enable said inner bridge piece to pass over said projection so that the projection may then enter said blade opening for maintaining the blade against accidental displacement from said head, said shoulder means being disposed between the longitudinal center of the head's concave face and a plane containing the head's longitudinal edges whereby a cooperatively positioned blade will be held bowed transversely by its engagement with the head's longitudinal side edges and said shoulder means.

8. A clamping head for a safety razor of the type including a guard; a head; and means for holding said head and guard together to clamp therebetween a wafer type blade having a longitudinal slot, said head being curved transversely and having a longitudinally extending rib on its concave face adapted to be received in the blade slot for guiding the blade endwise into cooperative position with respect to said head, and a flange on said rib extending from one end of the head only partially to the other end thereof and providing shoulder means spaced from and facing said head and being adapted to overlie a blade cooperatively positioned on said head, said shoulder means being disposed between the longitudinal center of the head's concave face and a plane containing the head longitudinal edges, whereby a cooperatively positioned blade will be held bowed transversely and displacement of the blade from the head will be yieldingly resisted.

9. A clamping head for a safety razor of the type including a guard; a head; and means for holding said head and guard together to clamp therebetween a wafer type blade having a longi-

tudinal slot, said head being curved transversely and having a longitudinally extending rib on its concave face adapted to be received in the blade's slot for guiding the blade endwise into cooperative position with respect to said head, and a flange on said rib providing shoulder means spaced from and facing said head and being adapted to overlie a blade cooperatively positioned on said head, said shoulder means being disposed between the longitudinal center of the head's concave face and a plane containing the head's longitudinal edges, whereby a cooperatively positioned blade will be held bowed transversely and displacement of the blade from the head will be yieldingly resisted.

10. A clamping head for a safety razor of the type including a guard; a head; and means for holding said guard and head together to clamp therebetween a resilient wafer type blade, said head having means to engage one face of the blade adjacent its longitudinal edges and other means to engage the other face of the blade intermediate its longitudinal edges, said two means being so relatively positioned as to hold the blade bowed transversely whereby displacement of the blade from the head is yieldingly resisted.

11. In a safety razor, a clamping head; a guard; a wafer type blade having an open ended longitudinal slot; and means for holding said head and guard together to clamp the blade therebetween, said head having a part adapted to be received in the blade slot for guiding the blade endwise into cooperative position with respect to said head, and shoulder means under which the so positioned blade lies, said shoulder means being disposed below a plane containing the longitudinal edges of said head whereby said shoulder means and said longitudinal edges will hold the blade bowed transversely to resist accidental displacement of the blade from the head while the razor is being assembled and prior to placement of the guard in assembled relation with respect to the head and blade.

12. In a safety razor, a transversely curved clamping head; a guard; a wafer type blade having a longitudinal slot; and means for holding said head and guard together to clamp the blade

therebetween, said head having a part adapted to be received in the blade slot for guiding the blade endwise into cooperative position with respect to said head, and shoulder means on said head under which the blade moves endwise into said position, said shoulder means being disposed between the longitudinal center of the head's concave face and a plane containing the head's longitudinal side edges, whereby the positioned blade will be bowed transversely by its engagement with said shoulder means and said head's longitudinal side edges.

13. A razor including a head member, a guard member, and a blade as set forth in claim 11 in which one of said members has a recess at one end and said blade has a tab accommodated in said recess so as to be easily grasped.

14. A razor as set forth in claim 12 in which the head member has a recess at one end and said blade has a tab accommodated in said recess so as to be easily grasped.

15. The combination of a razor clamping head and blade as set forth in claim 1 in which the head has a recess at one end and said blade has a tab accommodated in said recess so as to be easily grasped.

16. In combination, a safety razor clamping head; and a blade having an open ended slot, said head having a part adapted to be received in the blade slot for guiding the blade into cooperative position with respect to said head, and a recess at one end of said head, said blade having an end tab accommodated in said recess so as to be easily grasped for removal of the blade from the head.

17. In combination, a safety razor clamping head; and a blade having an open ended slot, said head having a part adapted to be received in the blade slot for guiding the blade into cooperative position with respect to said head, and a recess at one end of said head, said blade having an end tab turned out of the plane of the blade and being accommodated in said recess so as to be easily grasped for removal of the blade from the head.

JAMES E. CONNOLLY.
